UNITED STATES PATENT OFFICE.

STEVE MIZSAK, OF CLEVELAND, OHIO.

SHOE-HEEL.

Specification of Letters Patent. Patented Nov. 26, 1918.

1,286,054.

Application filed July 12, 1918. Serial No. 244,621.

To all whom it may concern:

Be it known that I, STEVE MIZSAK, a citizen of the United States, residing at Cleveland, in the county of Cuyahoga and State 5 of Ohio, have invented new and useful Improvements in Shoe-Heels, of which the following is a specification.

This invention relates to new and useful improvements in shoe heels and the principal object of the invention is to provide 10 means for making the bottom or lower riser of the heel removable, so that when the same becomes worn it may be replaced by a new one.

Other objects of the invention are to provide a plate connected with the heel and provided with downwardly projecting parts, a second plate secured to the removable or bottom riser and provided with upwardly projecting parts for engaging the projecting parts of the other plate and means for connecting said projecting parts together.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a vertical section through a heel provided with my invention.

Fig. 2 is a bottom view with the removable riser omitted.

Fig. 3 is a perspective view of the upper plate.

Fig. 4 is a like view of the lower or removable plate.

Fig. 5 shows a modification.

As shown in these views the heel 1 is composed of a plurality of risers 2, as is usual. In carrying out my invention I locate a plate 3 of metal or the like between the risers adjacent the bottom of the heel, the drawings showing the plate as carried by the second and third risers A and B. This plate is made of substantially the shape of the riser,

though of less dimensions so as to be entirely inclosed by the riser. The edges of said plate are scalloped as at 4 to leave T-shaped projecting portions 5. The ends of these T-shaped projections are bent at right angles to be pressed into the leather of the riser. The central part of the plate is cut and the cut part bent upwardly to form an ear 6, the edges of which are bent at right angles which make said ear of channel form. A lug 7 is secured to the plate a distance from said ear and being in the same plane therewith and this lug is provided with a screw threaded opening 8. The end of the plate is provided with an extension 9 and this extension is bent at right angles and its sides bent inwardly to form a channel shaped lug 10. This lug is provided with an opening 11 which is of larger diameter than the threaded opening and said openings are in the same plane. The risers A and B carrying said plate are slotted as at 12, said slot extending from the front face of the riser inwardly and adapted to receive both the lugs 7 and 10 and the risers are also provided with an opening 13 spaced a distance from the inner end of the slot for receiving the channel shaped ear 6. After the plate is placed in position on the risers these risers A and B are nailed to the other risers with the plate between them as shown in Figs. 1 and 2.

The bottom plate 14 is nailed to the lowermost riser 15 and the metal of said plate is cut and bent upwardly to provide the end lugs 16, having their outer edges curved as shown. 17 is the central lug extending at right angles to the end lugs 16 and provided with an opening 18, the end lugs being so located that the opening is centrally arranged in relation to said lugs. 19 is the innermost lug which is spaced a distance from the central lug and this lug is adapted to engage with the channel shaped ear 6 and the opening 13 when the plates are brought together. The lug 17 will pass between the end of the slot 12 and the lug 7 and the holes in these two lugs will be in alinement. The end lugs 16 will pass into the space between the lug 7 and the extension 9. A screw 20 is then passed through the opening 11 into the screw threaded hole 8 so that its end will engage the hole 18 in the lug 17 to hold the bottom riser in position.

It will thus be seen that when the bottom riser becomes worn the screw may be removed and the riser and bottom plate re-

moved and a new riser with the bottom plate attached put in its place. The bottom risers may be sold separately or if desired a new riser could be secured to the bottom plate by 5 a shoe maker.

The hole 11 in the extension 9 is made large enough to permit the head of the screw to pass therewith so that said head will be flush with the extension and said extension 10 is so formed as to cover up the end of the slot 12.

In the modification shown in Fig. 5 the lug 19' is made of curved shape as is also the ear 6'. In this manner these parts serve 15 to hold the bottom plate in position.

It is thought from the foregoing description that the advantages and novel features of my invention will be readily apparent.

I desire it to be understood that I may 20 make such changes in the construction and in the combination and arrangement of the several parts, provided that such changes fall within the scope of the appended claims.

What I claim is:-

25 1. A shoe heel having a portion thereof provided with a front opening and an interior opening, a plate located between said portion and the rest of the heel, a lug on said plate projecting into the interior opening and forming therewith a channel, a lug of channel form on the plate closing the front end of said front opening and having a hole therein, a third lug on the plate hav-

ing a screw-threaded opening therein and projecting into said front opening, a second 35 plate, a lug thereon engaging the channel, a second lug having an opening therein registering with the screw-threaded opening in the third lug, edge lugs engaging with the channel lug, a screw passing through the 40 registering holes in the lugs and a riser carried by the second plate.

2. A shoe heel having one of its risers 45 separate therefrom, a plate secured to said riser, a pair of lugs on said plate, one lug 45 having a hole therein and the other being of curved form, a second pair of lugs on said plate extended at right angles to the first pair, a portion of the heel having a central 50 opening and a front opening, a second plate located between said portion and the rest of the heel, a channeled lug at the front of the plate closing said front opening and receiving the right angular lugs, said channeled lug having an opening therein, the second 55 lug having a screw-threaded opening and extending into the front opening with its opening registering with the opening in the lug on the other plate, a second channeled lug of curved formation extending into the 60 central opening for receiving the curved lug on the other plate and a screw connecting the perforated lugs together.

In testimony whereof I affix my signature.

STEVE MIZSAK.
